DESIGN FOR A FISH LURE

Irene B. Albrecht and Ardath B. Kemp,
Portland, Oreg.

Application October 21, 1941, Serial No. 103,838

Term of patent 3½ years

To all whom it may concern:

Be it known that we, Irene B. Albrecht and Ardath B. Kemp, citizens of the United States, residing at Portland, in the county of Multnomah and State of Oregon, have invented a new, original, and ornamental Design for a Fish Lure, of which the following is a specification, reference being had to the accompanying drawing, forming part thereof, the present application being a continuation-in-part of application, Ser. No. D-100,304, filed April 10, 1941.

In the drawing:

The drawing has been shaded to represent contrasting appearance.

We claim:

The ornamental design for a fish lure, as shown and described.

IRENE B. ALBRECHT.
